(57) **CLAIM**

I claim the ornamental design for a adapter for computer card,
as shown.

DESCRIPTION

FIG. 1 is a front, left top isometric view of the adapter for
computer card;

FIG. 2 is a front, right, bottom isometric view thereof;

FIG. 3 is a top view thereof;

FIG. 4 is a right view thereof;

FIG. 5 is a front view thereof; and,

FIG. 6 is a back view thereof.

The broken lines in the drawings illustrate unclaimed portions
of the adapter for computer card and form no part of the
claimed design.
